SNAP OPERATING MECHANISM

Clarence T. Evans, Wauwatosa, Wis., assignor to
Cutler-Hammer, Inc., Milwaukee, Wis., a cor-
poration of Delaware

Application May 1, 1933, Serial No. 668,781

6 Claims. (Cl. 74—100)

This invention relates to improvements in snap operating mechanisms for control devices such as crane limit switches.

An object of the present invention is to provide a simplified and generally improved snap operating mechanism for control devices such as crane limit switches.

Another object is to provide a snap operating mechanism of the aforesaid character which is of the weight operated type and which provides for positive locking of its associated control device in opposite extreme positions.

Various other objects and advantages of the invention will hereinafter appear.

15 The accompanying drawings illustrate an embodiment of the invention which will now be described, it being understood that the embodiment illustrated may be modified in various respects without departing from the spirit and 20 scope of the appended claims.

In the drawings,

Figure 1 is a front elevational view of a limit switch having an operating mechanism embodying the invention associated therewith, an enclosing cover for such mechanism being shown in section.

Fig. 2 is a top view of the operating mechanism shown in Fig. 1, the enclosing cover for such mechanism and portions of the enclosing casing 25 for the limit switch being shown in section.

Fig. 3 is a perspective view of one of the operating parts shown in Figs. 1 and 2.

Fig. 4 is a vertical sectional view of the limit switch shown in Figs. 1 and 2.

35 Figs. 5, 6, 7 and 8 are schematic views of the operating mechanism, illustrating the same in different positions; and

Fig. 9 is a diagrammatic view illustrating application of the limit switch to the hoisting mechanism of an electric crane.

Referring to Figs. 1 and 2 of the drawings, the same illustrate a control switch 1 provided with a square operating shaft 2 which is rotatable in opposite directions between given extreme circuit controlling positions. Shaft 2 has an operating mechanism associated therewith including a lever 3 which is fixed to said shaft, a latching mechanism 4 which cooperates with said lever to lock said shaft in its extreme circuit controlling positions and a weighted operating arm 5 supported by said lever and operatively connected thereto by link 6. As hereinafter set forth arm 5 is movable in opposite directions with respect to lever 3 to bias shaft 2 for movement in opposite directions between its extreme circuit con-

trolling positions, and the latching mechanism 4 is controlled by the arm 5 to provide for operation of said shaft between such positions with a snap action.

More specifically, control switch 1 is provided with an enclosing casing 7 having suitable bearing parts on opposite ends thereof for supporting shaft 1. As shown in Fig. 2, the front end of shaft 1 is supported by a ball bearing 8 carried by plate 9 secured to the front wall of casing 7 by screws 10. Lever 3 is mounted upon a forwardly projecting portion of shaft 2, and as shown in Fig. 3 said lever is provided with a hub 11 having a square opening therein for receiving said shaft. Also as shown in Fig. 3, the hub 10 has a pair of spaced horizontally arranged arms 12—12 on one side thereof, a projecting lug 13 on its opposite side and a vertically arranged arm 14 on its upper side.

Arm 14 cooperates with the latching mechanism 4, and as shown in Figs. 1 and 2 said latching mechanism 4 includes a horizontally arranged lever 15 having its right hand end rotatably mounted upon a pin 16 fixed to plate 9 and having a forked portion 17 on its left hand end which carries a pin 18 having a roller 19 mounted thereon. Roller 19 cooperates with the upper end of the arm 14 on lever 3, and as shown in Fig. 3 said arm has concave faces 20—20 on opposite sides thereof for receiving said roller, and the end 25 thereof is shaped to provide an inverted V-shaped face 21. A spring 22 normally holds lever 15 in engagement with a stop 23, said spring being held under compression between said stop, and a downwardly projecting lug 24 on the under side 30 of said lever. Stop 23 is fixed to the front face of plate 9 and is located so as to hold lever 15 in position for engagement of roller 19 with the concave faces 20—20 on arm 14.

As hereinbefore stated, the weighted operating 40 arm 5 is supported by lever 3 and is operatively connected thereto by the link 6. Link 6 is arranged above the hub portion 11 of lever 3 and the left hand end thereof is rotatably mounted upon a pivot pin 25 carried by the arms 12—12 of 45 said lever while the right hand end thereof abuts the upper face of the lug 13. Arm 5 is arranged above the link 6 and is rotatably mounted at a point intermediate its ends upon a pivot pin 26 carried by the right hand end of link 6. The underside of arm 5 and the left hand end of link 6 are provided with abutting projections 27 and 28 and said arm carries a pair of screw stops 29 and 30 on the upper side thereof for engagement 50 with lever 15. Plate 9 is provided with stops 31 55

and 32 for limiting movement of the right hand end of arm 5 in opposite directions, and the right hand end of said arm is provided with an eye projection 33 for receiving a cable connection 34, 5 while the left hand end thereof is provided with a weighted projection 35.

- The function and operation of the aforescribed mechanism will now be more fully described in connection with Figs. 5 to 9, inclusive.
- 10 The control switch 1 may be of a type commonly employed on electric cranes to limit upward movement of the hoist block and in such installations a counterweight 36 is suspended from the right hand end of arm 5, as shown in Fig. 9, to 15 normally hold said arm in the position shown in Figs. 1 and 5. As shown in Fig. 9 the hoist block 37 is adapted to be raised and lowered by a mechanism including a cable 38 and winding drum 39 and upon movement of the hoist block into its 20 upper limit the same engages counterweight 36 to raise the same and permit counterclockwise movement of arm 5 under the action of its weighted projection 35.

When the arm 5 is in the position shown in 25 Figs. 1 and 5, roller 19 of the latching mechanism 4 engages the left hand concave face 20 on arm 14 and lever 3 is thus held against counterclockwise rotation to lock shaft 2 against movement out of one extreme position. During movement 30 of the hoist block 37 into its upper limit counterweight 36 is raised and arm 5 then moves in a counterclockwise direction under the action of its weighted projection 35 towards the position shown in Fig. 7. During such movement of arm 35 5 link 6 rocks therewith upon pivot pin 25, and as is apparent from Fig. 6 the entire weight of arm 5 is then supported upon said pivot pin. Thus the weight of arm 5 tends to effect counterclockwise movement of lever 3, such movement being prevented pending movement of said arm 40 into the extreme position shown in Fig. 7. During final movement of arm 5 into the extreme position shown in Fig. 7 the stop 30 on said arm engages lever 15 to move the same upwardly for 45 release of roller 19 with the left hand face 20 on arm 14. The weight of arm 5 then acts to effect snap movement of lever 3 and shaft 2 from the extreme position shown in Fig. 6 into the extreme position shown in Fig. 7. Upon movement 50 of the lever 3 into the position shown in Fig. 7 lever 15 of the latching mechanism is moved downwardly by its associated spring 22 and roller 19 then engages the concave face 20 on the right hand side of arm 14 to positively lock lever 3 and shaft 2 against movement in a clockwise direction.

Upon lowering of the hoist block 37 out of its 55 upper limit counterweight 36 acts to return arm 5 from the position shown in Fig. 7 to the position shown in Fig. 5. During such movement of arm 5 the same rotates upon pivot pin 26, and as is apparent from Fig. 8 the entire weight of said arm is then supported upon lug 13. Thus the weight of arm 5 tends to move lever 3 in a clockwise direction, such movement being prevented until return of said arm into the position shown in Fig. 5. During final movement of arm 5 into the position shown in Fig. 5 the stop 29 thereon engages lever 15 to move the same upwardly for 60 release of roller 19 with the right hand face 20 on arm 14. The weight of arm 5 then acts to effect snap movement of lever 3 and shaft 2 from the extreme position shown in Fig. 7 into the extreme position shown in Fig. 5 and the latching 65 mechanism 4 returns to normal position to lock 70 75 mechanism 4 returns to normal position to lock

said lever and said shaft against counterclockwise movement.

The control switch 1 may be of the type illustrated in Fig. 4. As shown in this figure an insulating base 40 is secured to the bottom wall of a frame 41 which forms a part of the switch enclosing casing 7. The switch mechanism includes a plurality of normally closed switches for controlling hoisting power connections for the hoist motor and a plurality of normally open switches for controlling dynamic braking connections therefor. The stationary contacts of said switches are mounted upon the upper face of base 40 and the movable contacts thereof are mounted upon shaft 2. Each of the normally closed switches is provided with a stationary contact 42 and a cooperating movable contact 43 which are arranged to the right of shaft 2 while each of the normally open switches is provided with a stationary contact 44 and a cooperating movable contact 45 which are arranged to the left of shaft 2. As is apparent, when the above described operating mechanism is in the normal position shown in Figs. 1 and 5 the switches are maintained in the positions shown in Fig. 4 to establish power connections for the hoisting motor. However, upon movement of the operating mechanism into the position shown in Fig. 7 the contacts 42 and 43 of the normally closed switches are disengaged to interrupt power connections 30 for the hoist motor and contacts 44 and 45 of the normally open switches are moved into engagement to establish dynamic braking connections therefor.

What I claim as new and desire to secure by Letters Patent is:

1. The combination with a control device having an operating shaft rotatable in opposite directions between given extreme positions, of a latching mechanism associated with said shaft 40 for locking the same against movement out of either of said extreme positions and a weighted operating member arranged above said shaft and supported thereby, said member being movable in opposite directions with respect to said shaft and being adapted to act by gravity when moved in either direction with respect to said shaft to bias the same in a corresponding direction, and said latching mechanism being releasable by said operating member upon movement of the latter 45 in opposite directions into given extreme positions.

2. The combination with a control device having an operating shaft rotatable in opposite directions between given extreme positions, a latching mechanism associated with said shaft for locking the same against movement out of either of said extreme positions, and an operating member arranged to one side of said shaft and normally supported by said shaft at points on opposite sides of the axis thereof, said operating member being movable in opposite directions with respect to said shaft to cause the same to act at either of said points for biasing of said shaft in either direction between said extreme positions, and said latching mechanism being releasable by said operating member to provide for snap movements of said shaft in opposite directions between said extreme positions under the biasing action of said operating member.

3. The combination with a control device having a horizontally arranged operating shaft rotatable in opposite directions between given extreme positions, a latching mechanism associated with said shaft for locking the same against

- movement out of either of said extreme positions, a lever fixed to said shaft and having horizontally arranged arms on opposite sides of the axis thereof, a link arranged above said shaft having 5 one end pivotally connected to one of said arms, and a weighted operating arm pivotally connected to the opposite end of said link and normally supported upon opposite sides of the axis of said shaft by the arms on said lever, said operating 10 arm being movable in opposite directions with respect to said shaft to shift the weight thereof to either of the arms of said lever to effect biasing of said shaft for rotation in either direction between said extreme positions, and said latching 15 mechanism being releasable by said operating arm to provide for snap movements of said shaft in opposite directions between said extreme positions under the biasing action of said operating arm.
- 20 4. The combination with a control device having a horizontally arranged operating shaft rotatable in opposite directions between given extreme positions, of a latching mechanism associated with said shaft for locking the same against movement out of either of said extreme positions, and an actuating lever carried by said shaft and normally supported at points upon opposite sides of the axis thereof, said lever being movable 25 in opposite directions with respect to said shaft and in a plane at right angles to the axis thereof to cause the entire weight of said lever to act at either of said points for biasing of said shaft in either direction between said extreme positions and said latching mechanism being releasable by 30 said actuating lever to provide for snap movement of said shaft in opposite directions between said extreme positions under the biasing action of said lever.
- 35 5. The combination with a control device having a control part movable about a fixed axis in opposite directions between given extreme positions, of a latching mechanism associated with said control part for locking the same against movement out of either of said extreme positions, and a weighted actuating member associated with said control part and movable in opposite directions with respect thereto to cause the same to act by gravity on said member at points on 10 opposite sides of the axis thereof for biasing of said member in either direction between said extreme positions, said latching mechanism being releasable by said actuating member to provide for snap movement of said control part in 15 opposite directions between said extreme positions under the biasing action of said actuating part.
6. The combination with a control device having a control part requiring movement in opposite directions between given extreme positions, of a weighted operating lever supported by said control part and movable in opposite directions with respect thereto, said operating lever when moved in either direction with respect to said 20 control part being adapted to bias the latter in a corresponding direction, and a latching mechanism associated with said control part for positively locking the same against movement out of either of said extreme positions, said latching 25 mechanism being releasable directly by said operating lever to provide for snap movement of said control part in opposite directions between said extreme positions under the biasing action of said operating part.
